UNITED STATES PATENT OFFICE.

JOHN H. WILTING, OF BUFFALO, NEW YORK.

FRACTURE-SETTING APPARATUS.

1,188,711.

Specification of Letters Patent. Patented June 27, 1916.

Application filed February 1, 1916. Serial No. 75,581.

To all whom it may concern:

Be it known that I, JOHN H. WILTING, a citizen of the United States, residing at Buffalo, in the county of Erie and State of New York, have invented certain new and useful Improvements in Fracture-Setting Apparatus; and I do declare the following to be a full, clear, and exact description of the invention, such as will enable others skilled in the art to which it appertains to make and use the same.

My invention relates to improvements in devices for setting fractured bones in the lower limbs or legs.

The object of the invention is to improve upon the general construction of devices of this class to such an extent as to provide an extremely simple, compact and light apparatus, yet one which will be highly efficient and durable, possessing a number of advantageous characteristics.

With this general object in view, the invention resides in certain novel features of construction and in unique combinations of parts to be hereinafter fully described and claimed, the descriptive matter being supplemented by the accompanying drawings which constitute a part of this application and in which,

Figure 1 is a side elevation of the improved apparatus showing its application to use; Fig. 2 is a top plan view; Figs. 3 and 4 are detailed horizontal sectional views taken in different planes above the base of the apparatus; Fig. 5 is an enlarged longitudinal section as seen on the plane indicated by the line 5—5 of Fig. 2; Fig. 6 is a vertical transverse section taken on the planes of the lines 6—6 of Fig. 5; Fig. 7 is an enlarged longitudinal section as viewed on the plane indicated by the line 7—7 of Fig. 3; Fig. 8 is a detail sectional view of one of the leg pulling devices; Fig. 9 is a top plan view thereof; Fig. 10 is a detail vertical section taken on the plane indicated by the line 10—10 of Fig. 8; Fig. 11 is an enlarged vertical section as viewed on the plane of the line 11—11 of Fig. 1; Fig. 12 is a detail longitudinal section as seen on the plane of the line 12—12 of Fig. 11; Fig. 13 is a vertical transverse sectional view as seen on the plane represented by the line 13—13 of Fig. 1; and Fig. 14 is a side elevation,

partly in section, of one of the leg supporting arms.

In specifically describing the invention shown in the drawings above briefly described, similar reference characters will be placed on corresponding parts throughout the several views and reference will be herein made to the numerous elements by their respective indices. To this end, the numeral 1 represents a horizontal base preferably of openwork formation for the sake of lightness, said base being adapted to rest upon a table top or the like 2 and to be secured thereon by an appropriate clamp 3. Rising from and formed integrally with the front end of the base 1, is an upright tubular boss 4 whose bore is intersected by a horizontal pin 5 shown most clearly in Fig. 5, the bore in question being adapted to receive therein the lower end of an upright crotch post 6 whose lower end is formed with vertical slots 7 receiving the pin 5, whereby the post 75 is held against rotation.

Mounted for vertical adjustment on the post 6 is a clamp 8 carrying a pelvic support 9 which is positioned in rear of the post 6, the portion of the latter above the aforesaid clamp being provided with a tubular pad 10 slidable vertically thereon to prevent injury to the patient when the apparatus is in use as shown in Fig. 1.

Formed integrally with the base 1 and 85 with the boss 4, and positioned immediately in rear of the latter, is a transversely disposed split bearing 11 having a horizontal axis, a thumb screw 12 being provided for the purpose of contracting said bearing 90 around a horizontal rigidly constructed shaft 13 which passes through and projects beyond the ends thereof. As shown clearly in Fig. 6, the shaft 13 is preferably of tubular formation for the sake of lightness and is equipped with end castings 14, having plugs inserted and secured therein, said castings being provided with flat horizontal ends 15 preferably of circular contour. Each of the ends 15 is formed with an upright threaded opening 16 and with a pair of sockets 17 spaced upon an arc described around said opening. Resting on the flat ends 15 are the flat rear ends 18 of a pair of sectional leg supporting arms 19 which 100 extend forwardly as shown clearly in the

several figures of the drawings. The ends 18 are formed with upright openings 20 alining with the openings 16, thumb screws 21 being passed through said openings 20 and threaded into the openings 16 (see more particularly Fig. 7). Thus, when the screws 21 are tightened, the two arms 19 will be so secured to the shaft 13 as to allow them to move vertically in unison only, this being 10 rather important for reasons yet to be described.

It is also important that, although the arms 19 be allowed to swing laterally independently of each other, they be automatically limited in their swinging movement to certain predetermined angular relations in respect to a medial line extending forwardly from the center of the post 6. This end has been accomplished by the 15 provision of the sockets 17 and rigid stop pins 22 which depend from the ends 18 of the arms 19. Thus, after the screws 21 are loosened and the ends 18 are raised, the pins 22 will rest on the ends 15 and the shaft 13. 20 This allows each arm 19 to be moved laterally in the desired direction, but after the proper amount of movement has been imparted thereto, the weight thereof will cause its pin 22 to drop immediately into the 25 socket 17 which it has approached while moving the arm. Obviously, therefore, the provision of the sockets 17 and pins 22, automatically limits the arms 19 in their 30 lateral movement.

35 As above stated, the arms 19 are sectional, being shown in the present embodiment of the invention as constructed of two tubular parts secured together by any appropriate style of slip joint such as that depicted at 40 23 in Fig. 14. This provision is made in order that when disassembling the entire apparatus, the arms 19 need not be of such a length as to render the same cumbersome.

45 For supporting the arms 19 in their numerous vertically adjusted positions, the vertically extensible and contractible stands 24 are employed, said stands having appropriate slides 25 on their upper ends through which the aforesaid arms pass, as shown 50 clearly in Fig. 1 of the drawings.

Mounted slidably on the front ends of the arms 19 is a pair of clamps 26 from which standards 27 rise, the upper ends of said standards being equipped with integral 55 longitudinally disposed tubular guides 28 which receive slidably therein a pair of leg pulling screws 29, the front ends of said screws preferably having T-heads 30 attached by appropriate connections 31 to a 60 pair of foot stirrups 32 adapted to be laced around the patient's feet in the manner depicted in Fig. 1. Formed in each screw 29 is a longitudinal groove 33 into which studs 34 project, said studs being threaded 65 through the front ends of the guides 28 as

shown clearly in Figs. 8 and 10. Thus, although the screws 29 may move longitudinally within the guides 28, they are held against rotation which would cause unnecessary pain to the patient being treated 70 by the machine, since even partial rotation of the screws would of course turn the stirrups 32 and would thus twist the injured leg of the patient.

For the purpose of shifting the screws 75 longitudinally to exert a pull on the stirrups 32, the hubs 35 of hand wheels 36 are threaded on the front ends of said screws in contact with the front ends of the tubular guides 28. Furthermore, in order that 80 the exact amount of endwise movement imparted to the screws may be readily ascertained, micrometer graduations 37 are formed on the hubs 35 for coöperation with indicators 37^a on the guides 28 (see more particularly Fig. 9).

It may be well to here explain that before the graduations 37 are employed, the clamps 26 are spaced equal distances from the ends of their respective arms 19, this 90 being possible by the provision of graduations 38 on the front sections of said arms. Thus, after the clamps in question have been properly set and the hand wheels 36 are turned to such an extent as to allow the 95 screws 29 to project rearwardly equal distances from the guides 28, the fractured limb can be pulled the necessary amount to set the fracture, and by proper use of the micrometer graduations 37, there will be no 100 danger of setting the break in such a manner as to cause the injured leg to be of a greater or less length than the other. It is to be observed that this result can be accurately obtained without the use of measuring both limbs as is now the usual custom 105 when using machines of the general class to which my invention relates. I therefore consider this an extremely salient feature of the invention.

In setting fractures as above mentioned, it becomes highly expedient to provide rests for the damaged parts of the limb or limbs. To this end, I have provided a number of substantially semi-cylindrical leg engaging 115 plates 39 having sockets 40 on their under sides receiving therein the laterally offset upper ends of standards 41, the latter being vertically slotted and pivotally and slidably secured by set screws 42 to clamps 43 120 125 slidably mounted on the arms 19. Obviously, the screws 42 allow the necessary adjustments of the standards 41 for properly positioning the rests 39 beneath the injured parts of the limbs.

Particular emphasis is laid upon the fact that the rests 39 are detachably connected with the standards 41. This is highly essential, since after the break has been set, either a bandage or a plaster of Paris cast 130

may be applied around not only the injured limb, but around the rest 39. The latter may therefore remain upon the patient's leg to serve as a splint, while the fracture is 5 knitting.

I wish to also emphasize that the rests 39 are formed of wood fiber or other appropriate material through which X-ray photographs may be taken, this being highly desirable in order that the condition of the 10 injured bone may be ascertained while the patient is positioned upon the apparatus.

I have hereinbefore stated the manner in 15 which the patient's legs may be prevented from varying in length when setting a fracture, but it is to be understood that the mounting of the arms 19 is essential in order that the desired results may be obtained. This particular mounting prevents one arm 20 19 from being positioned in a plane above the other, or vice versa, always insuring that the two arms be disposed in the same plane. Furthermore, the pins and sockets 22 and 17 respectively, serve to hold the aforesaid 25 arms in the same angular relations in respect to the medial line. Obviously, all of this is essential, since if both legs of the patient did not extend at the same angle from his body, accurate measurements could 30 not be made by the micrometer graduations 37 above described.

The entire apparatus is constructed of such proportions as to render it exceedingly light in comparison with other similar devices, the entire weight of the apparatus 35 being only thirty-five pounds. This allows the numerous parts of the invention to be disassembled and packed within a case of approximately the size of an ordinary suitcase, whereupon it may be readily taken 40 from place to place by physicians to be used when fractures are to be set at the patient's home or at other points remote from that at which the physician's apparatus is kept. 45 Also, the light weight of the improved apparatus and the compactness with which it may be packed in its case, renders it readily portable to numerous rooms in hospitals and the like where its use may be needed.

50 The case above described may be laid upon the table top 2 in rear of the pelvis support 9, after the apparatus has been assembled for use. Thus, said case may serve as a rest for the torso of the invalid.

55 I may here explain that I am aware that in devices similar to my own, pelvic supports similar to that disclosed by me have been used, but I am not aware that such supports have been rendered vertically adjustable as above described. This is essential, since when operating upon a corpulent person, the support must be much lower than otherwise, this being necessary in order that the post 6, even though it be padded, 60 65 may not cause pain to the invalid by im-

proper relation in respect to the human pelvis.

From the foregoing, when considered in connection with the accompanying drawings, the construction, manner of operation, 70 and numerous advantages of the invention will be readily understood without requiring a more extended explanation. In conclusion, however, I will state that the improved apparatus has been successfully employed by reputable physicians and hospitals in this country and has been found to be much more efficient, yet lighter and less costly, than other apparatuses heretofore employed. 75 80

I claim:—

1. A fracture setting apparatus comprising a pelvic support, a rigidly constructed transverse horizontal shaft revolvably mounted below the same, a pair of forwardly extending leg supporting arms pivoted at their rear ends to the ends of said shaft upon upright axes whereby they may be swung vertically only in unison and to the same extent, and whereby they may be also 90 swung laterally, means for limiting the lateral swinging of said arms to a number of fixed angular relations in respect to a medial line, means for supporting the arms in their vertically adjusted positions, leg pulling 95 means at the front ends of said arms, and means for preventing the patient's body from moving forwardly when said pulling means is in operation.

2. A fracture setting apparatus comprising a pelvic support, a rigidly constructed transverse horizontal shaft revolvably mounted below the same and having flat horizontal ends each formed with an upright threaded opening and with a series of upright sockets 100 spaced on an arc described around said opening, a pair of forwardly extending leg supporting arms having flat horizontal rear ends resting on the flat ends of the shaft and formed with openings alined with the aforesaid openings, upright set screws passing through the openings in the ends of the arms and threaded into those in the ends of the shaft, rigid stop pins depending from 105 said ends of the arms for reception in the aforesaid sockets, whereby to limit the horizontal movement of said arms to a number of predetermined angular relations in respect to a medial line, means for supporting the arms in their vertically adjusted 110 positions, leg pulling means at the front ends of said arms, and means for preventing the patient's body from moving forwardly 115 when said pulling means is in operation.

3. A fracture setting apparatus having a 120 leg supporting arm, a standard rising from said arm, and a fracture supporting plate having a detachable connection with the upper end of said standard, whereby it may be bound to the patient's limb to remain 125 130

thereon until knitting of the fracture takes place.

4. A fracture setting apparatus having a leg supporting arm, a standard rising from said arm, and a fracture supporting plate carried by said standard and constructed of non-pliable material through which X-ray photographs may be taken.

5. A fracture setting apparatus having a leg supporting arm, a standard rising from said arm, and a fracture supporting plate carried by said standard and constructed of non-pliable material through which X-ray photographs may be taken, said supporting plate having a detachable connection with the standard whereby it may be bound to the patient's limb to remain thereon until knitting of the fracture takes place.

6. A fracture setting apparatus comprising a pelvic support, a pair of leg supporting arms extending forwardly in respect thereto and capable of swinging vertically in unison only and to the same extent, said arms being also capable of laterally swinging, means for limiting the lateral movement of said arms to a number of predetermined angular relations in respect to a medial line, a pair of standards rising from the front ends of the arms and having longitudinally disposed tubular guides on their upper ends, a pair of horizontal screws mounted slidably but non-rotatably in said guides, foot stirrups connected to the rear ends of said screws, hand wheels having hubs threaded on the front ends thereof in contact with the front ends of the guides, coöperating indicating means on the hubs and guides whereby the amount of movement imparted to the screws by rotation of the hand wheels may be accurately determined, and means for preventing the patient's body from moving forwardly when the screws are moved by rotation of the hand wheels.

7. A fracture setting apparatus comprising a pelvic support, a pair of leg supporting arms extending forwardly in respect thereto and capable of swinging vertically in unison only and to the same extent, said arms being also capable of lateral swinging, means for limiting the lateral movement of said arms to a number of predetermined an-

gular relations in respect to a medial line, a pair of standards rising from the arms and having clamps slideable thereon, graduations on said arms whereby both standards may be set equal distances from the ends thereof, a pair of foot stirrups, a pair of pulling devices carried by the standards and connected to said stirrups for exerting a pull upon the patient's limbs, indicating means for accurately determining the amount of movement imparted to said stirrups by the screws, and means for preventing forward movement of the patient when said devices are in use.

8. A fracture setting apparatus comprising a pelvic support, a rigidly constructed transverse horizontal shaft revolvably mounted below the same, a pair of forwardly extending leg supporting arms pivoted at their rear ends to the ends of said shaft upon upright axes whereby they may be swung vertically only in unison and to the same extent, and whereby they may also swing laterally, means for supporting the arms in their adjusted positions, leg pulling means at the front ends of said arms, and means for preventing the patient's body from moving forwardly when said pulling means is in operation.

9. A fracture setting apparatus comprising a pelvic support, a pair of leg supporting arms extending forwardly in respect thereto, a pair of standards rising from the arms and having clamps slideable thereon, graduations on said arms whereby both standards may be set equal distances from the ends thereof, a pair of foot stirrups, a pair of pulling devices carried by the standards and connected to said stirrups for exerting a pull on the patient's limbs, indicating means for accurately determining the amount of movement imparted to said stirrups by the pulling devices, and means for preventing the patient's body from moving forwardly when said devices are in use.

In testimony whereof I have hereunto set my hand in presence of two subscribing witnesses.

JOHN H. WILTING.
